(57) **CLAIM**

The ornamental design for a rack/framework assembly, as shown and described.

DESCRIPTION

FIG. 1 is a perspective view from the front and left hand side of a rack/framework assembly, showing my new design;

FIG. 2 is a front view thereof;

FIG. 3 is a rear view thereof;

FIG. 4 is a right hand side view thereof, the left hand side view being identical;

FIG. 5 is a top plan view;

FIG. 6 is a bottom plan view thereof; and,

FIG. 7 is a front, left side perspective view of an alternative embodiment to that of FIGS. 1–6.
